UNITED STATES PATENT OFFICE

2,006,966

ELECTRIC SWITCH

Richard H. Schmitt, Schenectady, N. Y., assignor
to General Electric Company, a corporation of
New York

Application May 31, 1933, Serial No. 673,636

19 Claims. (Cl. 200—116)

My invention relates to electric switches of the type arranged to be operated with a snap action to open and closed circuit positions, and has for an object the provision of a reliable 5 and inexpensive operating mechanism for a switch of this character which readily lends itself to mass production.

While not limited thereto my invention is particularly applicable to thermally operated 10 switches for the control of fractional HP motors. Heretofore toggle mechanisms including an over-center spring have been used to operate switch contacts to open and closed circuit positions. A thermal device associated with the toggle 15 automatically opened the switch in response to a predetermined flow of current. However, much is yet to be desired in simplifying the construction of a switch of this character so that it can be readily assembled with or without 20 an overload tripping device and as a single or double-pole switch. It will be further understood that the space factor is important and consequently the switch must be very compact so that its overall dimensions will be in keeping 25 with the size of the motor it controls.

In carrying out my invention in one form thereof, I provide a switch arranged to be opened and closed with a snap action and to be opened automatically in response to a predetermined 30 overload current. More specifically, I provide a contact carrier with an inclined slot into which extends a sleeve supported on one end of an operating link. The other end of the link is fastened to a pivoted tripping bar normally 35 maintained in a predetermined position by means of a thermal overload device. The contact carrier is operated between opposite extreme 40 positions with a snap action by means of an overcenter spring having one end connected to the sleeve and the other end connected to an operating member. Upon the occurrence of an 45 overload, the thermal device permits the tripping bar to move to a tripped position to open the switch.

For a more complete understanding of my invention reference should now be had to the drawing wherein I have shown in Fig. 1 a plan view, partly in section, of a switch embodying my invention with certain parts removed; Fig. 2 is a side elevational view looking in the direction of the arrows 2—2 of Fig. 1; Fig. 3 is a side elevational view looking in the direction of the arrows 3—3 of Fig. 1; Fig. 4 is an exploded perspective view, partly in section, of the switch mechanism; Fig. 5 is a plan view of the operating knob and its support; Fig. 6 is a sectional elevation taken on the lines 6—6 of Fig. 5; Fig. 7 is a perspective view, partly in section, showing the mounting means for one of the switch ele-

ments; while Figs. 8 and 9 illustrate my invention applied to motor controlling circuits.

Referring to the drawing, I have shown my invention in one form as applied to a double-pole switch provided with a pair of stationary contacts 10 and 11 (Fig. 3) and cooperating movable contacts 14 and 15, preferably made of silver. The stationary contacts 10 and 11 are each rigidly secured against turning movement to a base 16 formed of insulating material by 10 means of metallic insert moulded in the base, such for example, as the insert 18 provided for the stationary contact 10 and shown in detail in Fig. 7. The lower portion 18a of the insert is knurled so that any tendency for the insert to turn is prevented. The upper portion 18c of the insert has its center drilled to form relatively thin side walls. The stationary contact member 10 has a base portion 10a provided with an opening 20 of the same diameter as the upper portion 18c of the insert 18. In assembling the stationary contact 10, it is placed on the insert and the thin walls of the insert 18 are spun over against the base portion 10a. The upper side of the base portion 10a is knurled around 15 the opening 20, as shown, so that the metal of the insert flows into the depressions formed by the knurling, thereby locking the stationary contact 10 to the insert 18 and to the base 16. The drilled portion of the insert 18 is also provided with threads so that a contact screw 22 20 can be held in threaded engagement with the insert. 25

The movable contacts 14 and 15 are operated to an open and closed circuit position by means 30 of a contact carrier arm 25 formed of insulating material and an operating mechanism 26. The contact carrier is pivotally supported upon a post 28 which has its lower end moulded in the base 16. Since the mountings for the movable contacts 14 and 15 are identical in construction, the mounting of only one, i. e., the contact 14, will be described in detail. As shown the contact 14 is welded to a double flexible 35 spring conductor 31, preferably formed of 40 bronze, one end 35 of which is connected to a terminal 37. The conductor 31 is normally held in spaced relation with the carrier 25 by means of a compression spring 34 mounted in a recess provided in the carrier. The other end of 45 the conductor 31 lies in a slot 36 and is provided with an enlarged or T-shaped portion 38 overlying the slot 36 to limit the outward movement of the conductor 31 by the spring 34. When the contacts are closed, the spring 34 is 50 compressed and insures a good wiping action on the contacts, the T-shaped end 38 of the conductor sliding in the slot as the spring is compressed. It will be understood that the other 55 movable contact 15 is mounted on the double 60

conductor 41 in exactly the same manner as described for the contact 14. As shown, grooves are provided on the carrier 25 to prevent the conductors 31 and 41 from coming into engagement with each other.

It may here be observed that if the switch is to be assembled as a single-pole circuit breaker it is only necessary to omit the assembly of one of the contact members and its related spring.

10 Continuing with the description of my invention, the contact carrier 25 is operated on its pivot by means of inclined slots 44 and 45 provided in a U-shaped metallic member 46 secured to the contact carrier 25. An operating link 48 for the contact carrier is provided with a pivot pin 49 upon which is rotatably mounted a sleeve 50 which lies in the inclined slots, and bears against opposite sides of the slots, or as shown against the opposite inclined plane surfaces formed by the slots, in moving the contact carrier to its open and closed positions. The opposite end of the operating link 48 is pivoted at 52 to a tripping bar 53. A U-shaped operating member 55 is provided having one arm 56 20 pivotally connected to the upper stationary plate 57 of a supporting frame by means of a pivot pin 58 secured thereto and extending through a hole 58a in the arm 56, the other arm 59 of the U-shaped operating member being supported in spaced relation with the lower plate 60 of the frame by the pivot pin 61. The metal frame plate 60 is secured to the base 16 by means of screws and the frame plate 57 is secured to the plate 60 in parallel spaced relation therewith by means of the posts 64 and 65.

30 In order to operate the switch to open and closed positions with a snap action, an overcenter spring 70 is provided having one end connected to the sleeve 50 and its other end connected to the mid-portion of a pin 72 secured to and extending between the arms of the U-shaped operating member 55. As shown, the overcenter spring 70 biases the operating link 48 for rotation about its pivot 52 in a counter-clockwise direction. An increased component of the force exerted by the spring 70 is thereby applied to the contact carrier 25 by reason of the engagement of the sleeve 50 with the inclined slots 44 and 45 to bias the movable contacts against the stationary contacts. Since this component of force applied to the contact carrier 25 rapidly increases as the sleeve 50 moves from an open circuit position to the closed position shown in Fig. 1, any tendency of the contacts 14 and 15 to rebound is effectively prevented. It will be observed that by operating the member 55 from the position shown in Fig. 4 in a counter-clockwise direction, the pin 72 is carried beyond the dead center position located at the pivot 52. Just as the spring reaches the dead-center position the component of force exerted by the spring on the operating link 48 is reduced to zero. Consequently, at this moment the only forces applied to the contact carrier are due 50 to the springs 34 associated with the contacts 14 and 15. The contact pressure is not diminished since the slots 44 and 45 and the link 48 are so arranged that no movement of the contact carrier occurs due to the forces exerted by the wiping springs 34. This is due to the fact that, as will be observed from Fig. 1, a line extending from the center of the pivot pin 52 to the point on the sleeve 50 engaging the slot 44 forms an obtuse angle slightly greater than 60 a right angle with the side of the slot engaged

by the sleeve. Consequently, an insufficient component of force is exerted by the spring 34 on the operating link 48 to move it along the slot. The contact carrier is thus effectively locked in the closed position. However as soon as the overcenter spring goes beyond this dead center position the operating link 48 is rotated in a clockwise direction to apply an increased component of the force of the spring against the slots 44 and 45 to operate the carrier to open 10 the switch.

15 If the slots 44 and 45 were not inclined with respect to the radius of the operating link 48, only a relatively small force would be available to maintain the contacts in their closed position. In accordance with the invention, however, an increased force exists to close the contacts against the opposing bias offered by the compression springs 34. Besides multiplying the force of the spring 70, the obtuse angle formed 20 by the slots and the link 48 minimizes the initial friction existing between the sides of the slots and the sleeve so that a faster movement of the contacts is secured, although as previously stated the angle is such that the spring 34 cannot initiate the movement of the contacts.

25 An extension 86 of the pin 72 engages the upper frame plate 57 at points indicated by the curved recesses 86a and 86b and thus limits the movement of the operating member 55 between 30 predetermined extreme positions. The operating member 55 is manually operated by means of a knob 80 formed of insulating material and loosely connected thereto. It will be observed, Figs. 2, 4, 5 and 6, that the knob 80 is supported 35 in a metallic plate 82, the knob being provided with a recess 84 into which the end 86 of the pin 72 extends. The recess 84 is larger than the end 86 of the pin 72 and provides a lost motion connection with the pin. Consequently, the 40 spring 70 is free to move the operating member in the recess independently of the operating knob 80. If this connection were not provided, it might be possible to turn the knob 80 until the dead center position were reached, at which 45 point the component of force exerted by the spring on the operating link 48 would substantially diminish. By reason of the lost motion action, however, the spring cannot be held in its dead center position. If the switch is either 50 being opened or closed, the spring is powerful enough to cause the operating member 55 to exert a hammer blow on the knob 80 by reason of the lost motion connection between the knob and the member 55. This hammer blow is of 55 sufficient strength to operate the switch from one position to the other irrespective of the will of the operator.

60 The construction of the knob 80 is shown in Fig. 6 and comprises two members 90 and 91 secured together by a metallic insert 92 moulded integrally with the member 90. One end 93 of the insert 92 extends through the other member 91 and is spun over against it. The upper portion 90 has an annular flange 95 which rests 65 against plate 82 and an annular central portion which extends through the opening provided in the plate 82. The outer end 96 of this central portion is rectangular. The member 91 is provided with a recessed portion 97 of rectangular 70 shape arranged to receive the rectangular end 96 of the upper member 90 so as to lock the two members 90 and 91 together. The dimensions are so selected as to permit the free movement of the knob 80 in the plate 82, between 75

two extreme positions determined by the engagement of a projection 90a on the knob with the plate at points indicated by the recesses 82a and 82b.

5 Continuing with the operation of my invention, it will be observed that the tripping bar 53 is pivotally mounted at one end to the post 65 provided with a sleeve 65a on one side of the bar and a washer 65b on the other side of the 10 bar, the sleeve and washer fixing the position of the bar 53 on the post. The tripping bar is maintained in the position shown in Figs. 1 and 4 by means of a latching member 99 secured to the tripping bar 53 and cooperating with a thermal 15 overload device 100. The thermal overload device 100 comprises a gear 101 supported by a sleeve 102 surrounding a stationary post 103 moulded in the base 16. The gear 101 is normally maintained stationary by reason of a solder film connecting the sleeve 102 to the post 103. A heater coil 105 surrounding the sleeve 102 is energized in response to the current flowing through the switch and upon the occurrence 20 of a predetermined overload causes the solder film to melt, thereby releasing the gear 101 for rotation.

Inasmuch as the operating link 48 is pivoted to the tripping bar 53 the force of the over-center spring 70 tends to rotate the tripping bar 30 in a clockwise direction about its pivot 65 as viewed in Fig. 1. Normally the tripping bar 53 is maintained in its normal position shown in Figs. 1 and 4 but as soon as the gear 101 is free to rotate, the tripping bar 53 rotates in a clockwise direction. Inasmuch as the contact operating sleeve 50 moves with the tripping bar it will be observed that the sleeve operates the contact carrier 25 to the open circuit position.

In order to reset the tripping bar 53, the 40 knob 80 and the U-shaped operating member 55 are rotated in a counter-clockwise direction. During this movement a notched end 118 provided on the arm 59 of the U-shaped member 55 engages an upturned projection 112 provided 45 on the tripping bar 53 so that the tripping bar is rotated in a counter-clockwise direction. When the operating member 55 reaches the limit of its movement the tripping bar 53 is in its 50 normal position with the latching member 99 engaging the teeth of the gear 101. Since the operating knob is now in the off position, it will be observed that the mechanism is trip free. That is to say, the knob 80 even though 55 operated cannot maintain a closed circuit if a current exists of sufficient magnitude to release the gear 101 because the tripping bar 53 must be in its normal position before the switch can be closed.

As I have stated, my invention is particularly 60 applicable to the control of fractional HP motors. A large majority of motors of this type is designed to be operated either on 110 volts or 220 volts, a change from one to the other voltage being made by connecting the motor windings 65 either in series or in parallel. Heretofore, heater coils have been provided for the particular voltage with the resistance of the coil proportioned for the particular voltage for the particular source of supply.

70 In accordance with the present invention the single heater coil 105 can be used for either 110 volts or 220 volts by reason of a double terminal member 115 provided with terminal screws, one of which secures one end of the heating coil 75 105 to the terminal member 115. Referring now

to Fig. 8 it will be observed that the line terminals 22 and 118 of the switch are connected to the 220-volt supply lines 120 and 121. The terminal 22 is connected to the stationary contact 10 while its cooperating movable contact 14 is connected to a terminal member 37. The movable contact 15, cooperating with the stationary contact 11 connected to the terminal 118, is connected to the double terminal member 115. The other end of the heater coil 105 10 is connected to a terminal member 128. The motor windings 130 and 131 are connected in series with each other and are connected to the switch by means of the terminal 37 and the terminal 128. With the movable contacts 14 15 15 in the closed position the current flows from the supply line 120, by terminal 22, contact 10, movable contact 14, terminal member 37, motor windings 130 and 131, terminal member 128, heating coil 105, the double terminal 20 115, movable contact 15, stationary contact 11 and from the terminal 118 to the other supply line 121.

In case the switch is to be connected to a 110-volt source of supply, the motor windings 23 130 and 131 are connected in parallel as shown in Fig. 9. The supply lines 140 and 141 representing the 110-volt source of supply are connected to the terminal members 22 and 118. Common sides of the motor windings 130 and 30 131 are connected to the terminal 37 while the opposite side of the motor winding 130 is connected to the terminal 115. The opposite side of the motor winding 131 is connected to the terminal 128. In this case it will be observed, 35 with the switch in the closed circuit position, that the current flows from the supply line 140 by terminal 22, stationary contact 10, movable contact 14, terminal member 37, and divides through the motor windings 130 and 131. The 40 current flowing through the motor winding 131 returns to the supply line 141 by terminal member 128, heating coil 105, movable contact 15, stationary contact 11 and the terminal member 118 while the current flowing through the motor 45 winding 130 is bypassed around the heater coil 105 by reason of the direct connection of the double terminal 115 to the movable contact 15. Consequently the current flowing through the heating coil is the same for either the 110-volt 50 or the 220-volt source of supply.

It is to be understood that the improved fastening means described for the stationary contacts is also used for the terminal members. Each terminal member is integrally secured to 55 the base 16 by means of a metallic insert moulded to the base and having its end spun over against its terminal member in the same manner as described in detail for the mounting of the stationary contact 10. A knurled surface providing 60 a plurality of ridges and depressions is provided adjacent the insert so that the metal flows into the depressions and prevents the terminal members from turning about their respective inserts.

In case it is desired to assemble the switch without the use of the thermal overload device 100, it is only necessary to insert a screw in the threaded opening 150 (Fig. 4) provided in the base plate 69, the upper end of the screw being 70 long enough to engage the tripping bar 53 to hold it in its normal position. The switch can then be operated as a conventional snap switch.

If a single-pole switch is desired it is only necessary to assemble one of the spring contact 75

members on the contact carrier, the other parts of the switch remaining the same as for the double pole breaker. It will therefore be seen that the identical switch members can be used 5 for single-pole or double-pole switches or for switches with or without thermal overload tripping devices.

While I have shown a particular embodiment 10 of my invention, it will be understood, of course, that I do not wish to be limited thereto since many modifications may be made, and I therefore contemplate by the appended claims to cover any such modifications as fall within the true spirit and scope of my invention.

15 What I claim as new and desire to secure by Letters Patent of the United States is:

1. In a switch, a switch member provided 20 with inclined plane surfaces, and operating mechanism for said switch member provided with means operable between predetermined positions with a snap action and alternately engaging said surfaces to operate said switch member between open and closed circuit positions with a snap action.

25 2. In an electric switch, a switch member provided with inclined plane surfaces, operating mechanism for said switch member provided with means operable between predetermined positions with a snap action for alternately engaging 30 said surfaces to operate said switch member between open and closed circuit positions with a snap action, and overload means associated with said mechanism for operating said switch member from said closed position to said open 35 position.

3. A switch mechanism comprising a switch member movable to open and closed positions said switch member being provided with an inclined slot, an operating link having one end 40 slidably engaging said slot, a pivot for the other end of said link, an overcenter spring operable between predetermined positions for rotating said link in opposite directions about said pivot so as to apply the force of said spring to said 45 switch member to operate it to said open and closed positions.

4. A switch mechanism comprising a switch member operable between open and closed circuit positions provided with a pair of inclined 50 surfaces spaced apart one from the other, an operating link one end of which cooperatively engages said inclined surfaces, a pivotal mounting for the other end of said link and an overcenter spring for rotating said link in opposite 55 directions about said pivotal mounting to operate said switch member between said positions with a snap action.

5. A switch mechanism comprising a switch member movable to open and closed positions, 60 said switch member being provided with an inclined slot a tripping bar movable from a normal position to a tripped position, an operating link having one end pivoted on said tripping bar and the other end slidably mounted within said 65 inclined slot, an overcenter spring for rotating said operating link about its pivot to operate said switch member to said open and closed positions and for biasing said tripping bar to said tripped position and thermal responsive means 70 for maintaining said tripping bar in said normal position.

6. A switch mechanism comprising a switch member movable to the open and closed positions, said switch member being provided with 75 a slot, an operating arm having one end slidably

engaging said slot, and an overcenter spring for snapping said arm from one position to another to operate said switch member, said link forming an angle with said slot so as to increase the force applied by said spring to said switch member when in said closed position and to lock said switch member in the closed position.

7. A switch mechanism comprising a switch member movable to open and closed positions, said switch member being provided with an inclined slot, a tripping bar movable from a normal position to a tripped position, an operating link pivoted at one end to said tripping bar and having its other end slidably engaging said slot, an operating member, an operating knob therefor loosely connected to said member, an overcenter spring connected to said operating link and to said operating member for rotating said link to operate said switch member to said open and closed positions, said loose connection permitting enough relative motion between said operating member and said knob to permit said overcenter spring to move past its dead center independently of said knob, and a thermally responsive means for holding said tripping bar in said normal position.

8. A switch mechanism comprising a contact carrier, an overcenter spring for operating said carrier to open and closed circuit positions, said carrier being provided with a groove along one side thereof, a flexible conductor mounted in said groove and having a projecting end extending to the opposite side of said carrier and a compression spring normally biasing said conductor away from said carrier.

9. An electric switch provided with relatively movable contacts, a contact carrier provided with a depression at one side thereof, a flexible conductor extending from one side of said carrier through said depression to the other side of 40 said carrier, said end of said conductor being provided with an enlarged end for engaging said carrier, a compression spring between said conductor and said carrier for normally biasing said enlarged end against said carrier and an overcenter spring for operating said carrier to open and closed circuit position with a snap action.

10. An electric switch provided with a base formed of insulating material, contact terminals 50 secured to said base at opposite ends thereof, a contact carrier pivotally mounted upon said base, an overcenter spring connected to one side of said carrier for operating said carrier to open and closed circuit positions, movable contact 55 members comprising resilient electrical conductors having one end fixedly secured to said terminal members said conductors extending from said terminal members along one side of said carrier, the opposite ends of said conductors extending from said one side to the other side of said carrier and a compression spring mounted between said conductors and said carrier for normally maintaining said conductors in spaced relation with said carrier, the other ends of said conductors being arranged to engage said carrier.

11. An electric switch provided with a base of moulded insulating material, a metallic insert moulded integrally with said base and having an end extending above said base, a switch member provided with an opening for receiving said end of said insert, said switch member being provided with a knurled surface adjacent said opening providing a plurality of depressions 75

- so that when said end of said insert is spun over against said switch member the metal flows into said depressions to secure rigidly said switch member to said insert.
- 5 12. An electric switch provided with a moulded insulating base, a metallic insert moulded integrally with said base and provided with a projecting end, a stationary contact provided with an opening for receiving said end 10 of said insert, the area surrounding said hole being knurled to form a plurality of depressions into which metal can flow when said end of said insert is spun over against said stationary contact thereby locking said stationary contact to said insert and to said base.
- 10 13. An electric switch provided with an insulating base, a pair of stationary contacts, a pair of load terminals secured to one portion of said base and connected to said stationary contacts, a pair of movable contacts, means for operating said movable contacts between open and closed circuit positions, thermal responsive means for operating said contacts from said closed circuit position to said open circuit position, a plurality of load terminals, connections for connecting one of said terminals directly to one of said movable contacts, connections for connecting said other contacts in series with each other and with said thermal responsive device and said other movable contact whereby said switch can be connected to sources of supply having different values of voltage without changing the adjustment of said thermal responsive device.
- 15 14. An electric switch provided with a supporting base, a pair of stationary contacts for said switch, a pair of movable contacts, means for operating said movable contacts into and out of engagement with said stationary contacts with a snap action, a thermal overload device for operating said contacts from a closed circuit position to an open circuit position, line terminals provided on one portion of said base and three load terminals provided at the opposite end of said base said overload device being connected in series with two of said terminals and with one of said stationary contacts and one of said movable contacts, the other of said load terminals being connected to the other of said stationary and movable contacts whereby said switch can be connected to either of two voltages without changing the characteristics of said overload device.
- 20 15. A motor starting switch for a motor provided with a pair of field windings, line terminals for said switch, cooperating contacts operable to open and closed circuit positions, operating means for said contacts, thermal responsive means for operating said contacts from said closed circuit position to said open circuit position, a heater coil for said thermal responsive means, three load terminals supported by said base, connections for connecting one of said terminals in series with one of said stationary and movable contacts, connections for connecting two of said load terminals in series with each other, said heating coil and said other movable and stationary contacts whereby said motor windings can be connected in series with each other and to two of said terminals, said heater coil being included in said series circuit and so that said motor windings can each be connected to a pair of said terminals so that said heater coil is connected only in series with one of said windings.
- 25 16. A switch comprising a movably mounted switch member provided with a pair of plane operating surfaces, an operating member for said switch member, and means mounting said member for movement between predetermined positions in a constrained path extending at an angle with said surfaces and for sliding engagement with said surfaces alternately to operate 10 said switch member between open and closed circuit positions.
- 30 17. A switch comprising a movably mounted switch member provided with a pair of parallel operating surfaces, an operating member for 15 said switch member slidably engaging said surfaces, means mounting said operating member for movement between predetermined positions in a constrained path extending at an angle with said surfaces, and spring means for moving said 20 operating member with a snap action between predetermined positions to operate thereby said switch member between open and closed circuit positions.
- 35 18. A switch mechanism comprising a switch 25 member movable to open and closed positions, said switch member being provided with an inclined slot, an operating link having one end slidably engaging said slot, an overcenter spring operable between predetermined positions for 30 operating said link in opposite directions so as to apply the force of said spring to said switch member to operate it to said open and closed positions, a tripping bar biased for movement from a normal position to a tripped position, 35 overload responsive means retaining said tripping bar in said normal position and operable on overload to release said bar for movement to said tripped position, and connections between said tripping bar and said operating link for 40 operating said switch member from said closed position to said open position upon movement of said tripping bar from said normal position to said tripped position.
- 40 19. A switch comprising a switch member 45 movable to open and closed positions, said switch member being provided with an inclined slot, an operating link having one end slidably engaging said slot, pivot means for the opposite end of said link, an over-center spring one end of which 50 is connected to said link, an operating handle connected to the opposite end of said over-center spring for moving said spring with reference to said pivot means to rotate with a snap action said link in one direction or the other, said link 55 and said slot applying the force of said spring to said switch member to operate it to said open and said closed positions, a tripping bar biased for movement from a normal position to a tripped position, overload responsive means retaining said tripping bar in a normal position and operable on overload to release said bar for movement to said tripped position, said tripping bar operably connected to said operating link for operation independently of said handle 60 of said switch member from said closed position to said open position as said tripping bar moves from said normal position to said tripped position, and means operable by said handle for returning said tripping bar to said normal position 65 prior to the return of said switch member to said closed position.

RICHARD H. SCHMITT.
